UNITED STATES PATENT OFFICE.

JISAKU KODAMA, OF CORONADO, CALIFORNIA.

GAMING AND AMUSEMENT DEVICE.

1,171,728.

Specification of Letters Patent. Patented Feb. 15, 1916.

Application filed June 7, 1915. Serial No. 32,738.

To all whom it may concern:

Be it known that I, JISAKU KODAMA, a subject of the Emperor of Japan, residing at Coronado, in the county of San Diego 5 and State of California, have invented certain new and useful Improvements in Gaming and Amusement Devices, of which the following is a specification.

My invention relates to a gaming and 10 amusement device in the form of a merry-go-round, the winning of the prize being dependent upon the device stopping at a particular place or places and it is also adapted for use as a toy for the amusement 15 of children.

The objects of my invention are: First, to provide a device of this class in which the figures for revolution may be horses, 20 automobiles, boats, human figures and the like and are interchangeable; second, to provide a device of this class on the central post of which may be mounted a plurality of spiders with different characters on each spider; third, to provide a device of this 25 class in which the base portion may be used as a portion of the casing and which is provided with a cover forming a casing for the device; fourth, to provide a device of this class which may be operated by hand or 30 with a motor if desired; and fifth, to provide such a device that is simple and economical of construction, durable, easily installed and easily operated.

With these and other objects in view as 35 will appear hereinafter, my invention consists of certain novel features of construction, combination, and arrangement of parts as will be hereinafter described in detail and particularly set forth in the appended 40 claims, reference being had to the accompanying drawing and to the characters of reference thereon which form a part of this specification, in which—

Figure 1, is a perspective view of my device with some of the figures shown mounted thereon and with the cover removed, Fig. 2, is a fragmentary sectional view of the same, Fig. 3, is a perspective view of the cover for the device, and Fig. 4, is a 50 perspective view of a device for operating the same by hand.

Similar characters of reference refer to similar parts throughout the several views.

The base piece 1, disk 2, spider 3, spider 4, central post 5, clamp 6, figure 7, figures 8,

figures 9, operating device 10, cover 11, and character piece 12 constitute the principal parts of my structure.

The base 1 is in the form of a round box provided with a bottom 1^a which is provided with a central lug bearing 1^b and with upwardly extending annular portion 1^c which is provided with a cut-away portion 1^d adapted for the cover 11 to fit over. Pivottally mounted centrally on the bottom 60 in the bearing 1^b and extending vertically therefrom is the central post 5 and rigidly secured thereto is a disk 2 which is preferably glass so that different scenery representing different amusements may be secured to the lower surface and will show through said glass and on the inner surface of the wall 1^c and secured thereto is the annular piece 12 which is provided with a row of characters preferably numbers and 65 it is supported by means of the annular piece 1^e on the inner surface of the wall 1^c. Secured to this central post 5, and above the disk 2, is the spider 3 which is provided with a plurality of arms 3^a preferably 70 six in number. These arms 3^a are provided with joints 3^b adapted to allow the pivotal movement of the extended ends of the arms 3^a upwardly when desired. Mounted on the extended end of the arms are indicating 75 needles 3^c which are adapted to indicate the winning numbers which are immediately below these needles, on the annular piece 12 as hereinbefore described. On each of the arms 3^a are also secured the figure supporting devices 3^d which are adapted for supporting the figures 9 thereon and are made so that the extended portion may be spread 80 so that the figures to be mounted thereon, may be readily placed and so that the figures are interchangeable for different kinds of figures. The spider 3 is secured to the post by means of set screws 3^e so that the spider may be readily adjusted or removed 85 from the post entirely if desired. Above 90 this spider 3 and similarly secured to said central post is another spider 4 provided with a plurality of extended arms 4^a preferably three in number. On the outward extended ends of which are secured small 95 strings or cables 4^b upon which are suspended the figures 8 so that when the post 5 revolves the figures swing thereon. These arms 4^a are also provided with joints 4^c so 100 that they may be pivotally moved upwardly 105 110

at their extended ends. Secured to the post at the top is a clamp 6 which is provided with an extended lug 6^a upon which is mounted the figure 7 which is also carried around with said post in its revolution. In one side of the base piece 1 is provided a slot 1^d adapted to allow the insertion of the toothed end of the operating device 10. This operating device 10 is a U-shaped piece provided with inwardly extending teeth 10^a and with a compression spring 10^b near the middle thereof tending to hold the teeth 10^a apart.

In using the operating device the teeth 15 are pressed tightly against the disk near its outer edge so as to hold it firmly and the disk given a quick jerk in one direction and releasing the spring 10^b throwing the teeth 10^a apart and the starting device removed therefrom, however, it is obvious that the 20 device may be operated by means of a motor, the belt and wheels secured to the central post 5 if desired. Mounted over the top of the device is the cover 11 which fits down 25 over the cut-away portion 1^d of the base piece 1, thus forming a round box or casing for the device for inclosing the same.

Though I have shown and described a 30 particular construction, combination and arrangement of parts, I do not wish to be limited to this particular construction, combination and arrangement but desire to include in the purview of my invention the construction, combination and arrangement 35 substantially as set forth in the appended claims.

It is obvious that with this construction, 40 there is provided a gaming and amusement device in the form of a merry-go-round; that the needle will indicate the winners by pointing to the characters on the annular piece below; that the figures mounted on the 45 arms of the spider 4 are readily removable so that other figures may be placed thereon of various kinds and characters as desired; that the figures suspended on the arms 4^a will swing with the revolution of the central post 5; that the figure 7 mounted on the upper end of the central post will revolve with 50 said central post; that the operating device 10 provides simple means for spinning the disk 2; that the upper extended end of the device, including the spider 4 and clamp 6, may be removed and the figures removed 55 from the spider 4 and the device still be a good and sufficient gaming device; that the various figures on the same provide amusement with its operation, either for a gaming device or amusement as desired; that the 60 device as a whole is simple and economical of construction, durable, easy of operation and the figures readily interchangeable and that the cover 11 incloses the device in a simple casing.

65 Having thus described my invention, what

I claim as new and desire to secure by Letters Patent, is

1. In a device of the class described, the combination of a stationary annular base piece, a post centrally and revolvably mounted therein, a disk secured thereto, an annular piece secured to the inner surface of said base portion provided with an annular row of characters thereon, a spider secured above said disk adapted to revolve therewith, a figure representing a racing device mounted on each of said arms and means to facilitate the revolution of said disk. 75

2. In a device of the class described, the combination of a stationary annular base, a disk revolvably mounted therein, a spider secured above said disk adapted to revolve therewith, a figure representing a racing device mounted on each of said arms, means to facilitate the revolution of said disk and another spider secured above said first mentioned spider provided with a plurality of suspended figures thereon adapted to swing. 85

3. In a device of the class described, the combination of a stationary annular base portion, an annular piece provided with an annular row of characters thereon, a disk revolvably mounted therein, a spider secured above said disk adapted to revolve therewith, a figure representing a racing device mounted on each of said arms, means to facilitate the revolution of said disk, another spider secured above said first mentioned spider provided with a plurality of suspended figures thereon adapted to swing, a 95 clamp piece mounted on the upper end of said central post provided with an outwardly extending lug and a figure mounted on said outwardly extending lug adapted to 100 revolve with said post.

4. In a device of the class described, the combination of a stationary annular base portion provided with an annular row of characters thereon, a disk revolvably mounted therein, a spider secured above said disk adapted to revolve therewith, a figure representing a racing device mounted on each of said arms, means to facilitate the revolution of said disk, another spider secured above said first mentioned spider provided with a 110 plurality of suspended figures thereon adapted to swing, a clamp piece mounted on the upper end of said central post provided with an outwardly extending lug and a figure mounted on said outwardly extending lug adapted to revolve with said post and a cover for said base piece. 115

5. In a device of the class described, the combination of a round base piece, a vertical post centrally and revolvably mounted therein, a transparent disk secured to said post, an annular piece secured to said base piece provided with an annular row of characters thereon, a spider secured to said post above said disk provided with a plurality of fig- 125 130

ures mounted thereon, indicating needles secured to the outwardly extending ends of the arms of said spider pointing to the row of characters on said annular piece.

- 5 6. In a device of the class described, the combination of a round base piece, a vertical post centrally and revolvably mounted therein, a transparent disk secured to said post, an annular piece secured to said base piece, 10 provided with an annular row of characters thereon, a spider secured to said post above said disk provided with a plurality of figures mounted thereon, indicating needles secured to the outwardly extending ends of 15 the arms of said spider pointing to the row of characters on said annular piece and another spider secured to said post above said first mentioned spider provided with a plurality of figures suspended from the arms of

said spider adapted to swing thereon with 20 the revolution of said post.

7. In a device of the class described, the combination of a round base piece, a vertical post centrally and revolvably mounted therein, a transparent disk secured to said post, 25 an annular piece secured to said base piece provided with an annular row of characters thereon, a plurality of spiders secured to said post above said disk provided with a plurality of figures mounted thereon indicating needles secured to the outwardly extending ends of the arms of one of said spiders.

In testimony whereof, I have hereunto set my hand at San Diego, California this 2nd 35 day of June 1915.

JISAKU KODAMA.
